GASKET CUTTER

Raymond A. Hall, Fort Valley, Ga.

Application February 25, 1932. Serial No. 595,198

3 Claims. (Cl. 164—82)

My invention relates to means for accurately cutting sheet material.

My invention relates specifically to a gasket cutting device which is especially adapted for 5 use with a hand brace or with a machine actuator.

It is an important object of my invention to provide a device of this kind which cleanly and accurately cuts gaskets of very narrow width, and which is especially constructed to enable this 10 to be done.

It is also an important object of my invention to provide a simple and inexpensive device of this kind in which ruggedness, and accuracy in results is not sacrificed, despite its low cost.

15 Other objects and advantages of my invention will be apparent from a reading of the following description and drawing, wherein for purposes of illustration, I have shown a preferred embodiment of the invention.

20 In the drawing:—

Figure 1 is a general side elevational view of the device of the invention.

Fig. 2 is a top plan view thereof, showing a portion thereof in section and

25 Fig. 3 is an elevational view of Fig. 1, taken from the right thereof.

Referring in detail to the drawing, wherein like numerals refer to like parts throughout the same, the numeral 5 refers generally to a suitable 30 bed of metal or other material of a softer character than the cutters employed with the device, and the numeral 6 refers to a sheet of gasket material to be worked upon by the cutters of the device.

35 At a suitable place in the bed 5 is an aperture to receive freely the centering point of the device so as to permit free movement toward the bed of the device during the cutting operation, and to properly maintain the same on a constant axis of rotation.

The device comprises a shank 8 for reception in the brace chuck or other chuck, and this is formed with a generally cylindrical enlargement 45 9 on its lower end and provided with a concentric sharpened point 10. The cylindrical enlargement 9 is provided with a diametrical opening 11 through which the round cutter bar 12 snugly slides. The numeral 13 represents a thumb screw 50 or its equivalent operating through the sides of the enlargement 9 for engaging a flattened portion 15 on the side of the cutter bar to lock the cutter bar with respect to the enlargement 9. On one end of the cutter bar is carried a block 55 16 which has operating therein a thumb screw

17 for locking the body on the rod at a selected position thereof.

The block 16 has between arms 18, and extending from its lower side a roller 19 for a purpose to be indicated. The opposite end of the 60 cutter bar is formed with a reduced spindle 20.

Upon this reduced spindle is adapted to be placed a pair of dished cutter disks 21, 22, which have hubs 23, 24, whose exterior diameter is approximately the same as that of the cutter 65 bar 12.

It will be observed that these cutters 21, 22, have their concavities facing radially inwardly. The hub 23 of the cutter 21 extends from the radially outward side of the cutter 21, while the 70 hub 24 of the cutter 22 extends radially inwardly therefrom. It will be seen that the end of the hub 24 engages the shoulder 25 on the cutter bar to prevent further inward movement of the cutter 22. A plurality of washers 26 of the same 75 size as the cutter bar 12 separates the cutters 21, 22 to the desired distance, while another plurality of washers 27 is retained on the spindle 20 and engaging the outward end of the hub 23 for securing the cutter 21 in the proper relationship with the cutter 22.

Suitable lock nut means 28 is screwed on the end of the shank 20 for maintaining the structure just recited.

It will be observed that the washers 27, 26 85 may be disposed in various relation to the cutters 21, 22, on the spindle 20 so as to give different results, when the device is applied for cutting the gasket material.

It will be observed that the cutters 21, 22 may be very closely related, since the washers 26, when removed, will permit the convex face of the cutter 22 to seat with the concaved face of the cutter 21 whereby to enable the cutting of a narrower gasket than has heretofore been possible with a tool of this particular type.

The disks are made concavo convex in order to better follow the curvature of the circle described and cut more cleanly, especially when operating closer together and on small gasket work.

When using the cutter with a hand brace the roller 19 is very useful for balancing the pressure upon the gasket material. The cutters 21, 22 are adapted to engage the gasket material just in advance of the roller 19 so as to have cutting engagement with the gasket material prior to the engagement with the gasket material or the bed 5 of the roller 19, so as not to disturb the axial alinement of the centering device 10 105 110

and its engagement with the opening 7 in the bed 5, and to insure accurate cutting of the gasket within fine limits.

Though I have shown and described herein 5 a preferred embodiment of the invention, it is to be understood that changes in size, shape and materials and arrangement of parts can be made consistent with the spirit of the invention and the scope of the subjoined claims.

10 Having thus described my invention, what I claim as new is:—

1. The combination with a gasket cutter including an axially rotatable member, a transverse cutter bar carried thereby, and a plurality of 15 cutter disks adjustable on the cutter bar, of a plurality of washers for interposition on the bar between the cutter disks for adjustably spacing them and between the disks and a portion of the bar for spacing the disks from the portion, 20 and nut means threaded on the bar for maintaining the washers and disks in adjusted positions, said disks being convex concave and capable of being substantially nested for cutting a very narrow gasket, the concave sides of the disks being 25 based radially inwardly with respect to the cutter bar to facilitate the operation of the cutter and cut cleanly.

2. In a rotary cutter, an axially rotatable mem-

ber carrying a transverse cutter bar, a reduced threaded portion on one end of the cutter bar, and on the reduced portion a pair of convex-concave cutter disks disposed with their convex sides radially outwardly, a radially outward tubular extension on the convex side of the radially outward disk, a radially inward tubular extension on the concave side of the radially inward disk, nut means on the reduced threaded portion for locking the disks in spaced and nested positions.

3. In a rotary cutter, an axially rotatable member carrying a transverse cutter bar, a reduced threaded portion on one end of the cutter bar, and on the reduced portion a pair of convex-concave cutter disks disposed with their convex sides radially outwardly, a radially outward tubular extension on the convex side of the radially outward disk, a radially inward tubular extension on the concave side of the radially inward disk, nut means on the reduced threaded portion for locking the disks in spaced and nested positions, and spacer means receivable on the threaded reduced portion between and inward and outward of the disks and radially inward of the nut means for adjustably locking the disks on the reduced threaded portion.
